UNITED STATES PATENT OFFICE.

SAMUEL SUEKOFF AND WILLIAM W. GLEASON, OF CHICAGO, ILLINOIS; SAID GLEASON
ASSIGNOR, BY MESNE ASSIGNMENTS, TO A. F. McKEOWN, JR., OF CHICAGO, ILLINOIS.

SPRING-CUSHION CONSTRUCTION.

Application filed February 1, 1923. Serial No. 616,250.

To all whom it may concern:

Be it known that we, SAMUEL SUEKOFF and WILLIAM W. GLEASON, citizens of the United States of America, and residents of Chicago, Cook County, Illinois, have invented a certain new and useful Improvement in Spring-Cushion Construction, of which the following is a specification.

The object of our invention is to provide a method by means of which to economize in the fabric necessary to be used, and to also economize time and labor in the sewing of the parts together, and yet provide a spring cushion, or the like, which shall maintain the springs thereof under compression in an upright position, isolated from each other by fabric.

Our invention has certain other objects in view which will more fully appear hereinafter, and in addition to the method to be described, consists in certain novel completed constructions which will be fully described.

In the accompanying drawings—

Fig. 1 is a top plan view of a portion of a continuous length of the fabric having thereon sewing indicating lines.

Fig. 2 is a perspective view of the collective spring enclosing compartments.

Fig. 3 is a perspective view of a part of one of the divisional fabric partitions.

Fig. 4 is a diagrammatic view illustrating the arrangement of the sewing machines relative to each other and to the continuous length of marked and cut fabric, the sewing machines being indicated diagrammatically, whereby the partition strips are sewn along the lines marked on the continuous length of fabric.

Fig. 5 is a perspective view of a portion of the top piece with the partitions sewn thereto.

Fig. 6 is a view similar to Fig. 4, illustrating the position of the sewing machines by means of which the other edges of the partition strips are sewn to the bottom piece and the boxing portion of the top and bottom pieces are sewn together.

Fig. 7 is a perspective view of a portion of the completed structure comprising the multiple collective spring enclosing compartment.

Fig. 8 is a top plan view of the cushion

with top cover removed to show the internal arrangement, and

Fig. 9 is a perspective view of a single spring retainer.

Our invention considered broadly is the method of constructing spring cushions or cushion foundations, for use in furniture, coach and motor building, and comprising a covering of burlap or like material, consisting of pieces sewn together and enclosing a plurality of springs.

More specifically the invention pertains to the method of assembling the various pieces of fabric that make up the cover, including the top, bottom and side pieces, the partition members, forming the spring enclosing compartments, and the spring retainers, by which the individual springs are assembled in rows for insertion as units into the spring compartments.

The method employed in constructing the multiple collective spring enclosing compartments will first be described. A continuous length of fabric, preferably burlap, is cut longitudinally to a width at least equal to the depth or width of the cushion to be made. The length of the fabric for convenience should be approximately three-hundred yards so that a continuous length of fabric is provided of a width equal to one dimension of the cushion to be made. As shown, two continuous lengths of the fabric are provided to constitute the top and bottom pieces A and B—Fig. 2—of the cushion, which also constitute the top and bottom of the collective spring enclosing compartments. Continuously along one face of the length of fabric, as shown in Fig. 1, continuous sewing indicating lines 2 are marked. The cutting and marking is done simultaneously by a machine in a well known manner. When this length of the fabric is cut transversely to obtain the dimension of the cushion transversely to that obtained by the longitudinal cutting of the fabric, the top and bottom pieces A and B are obtained, which are sewn together by the seams $a-a$,

thus providing the boxing or side walls A^2 of the cushion. Therefore, in cutting the continuous length of the fabric longitudinally, it should be cut of a width sufficient to provide the top or bottom portion, plus one-half the height of the spring under com-

pression, plus the seam allowance. In some instances, however, it is necessary to provide for the tacking of the assembled springs to the wooden framework of a chair or the like, and under such conditions the continuous length of the fabric is cut the width or depth of the cushion plus sufficient material to provide a flap by which the assembled springs are tacked to the framework. It is manifest, however, that in any case the continuous length should be longitudinally cut of at least a sufficient width to constitute either a top or bottom piece for the cushion to be made.

15 In order to provide for the partitions C of the compartments, continuous strips are cut of the fabric of a width equal to the height of the springs under compression plus two seam allowances.

20 The partition strips C are sewn to the top and bottom pieces in a manner to be now described: Having reference to Fig. 4, sewing machines are conventionally represented at D, the number of such machines employed corresponding to the number of seams. These sewing machines are arranged in echelon one behind the other in such lateral position so that the needle bar d of each machine coincides with an indicating line 2.

25 Inasmuch as it is impossible to distinguish the top piece from the bottom piece in the completed cushion, for purposes of description we will refer to the continuous length to which the partition strips C are first sewn as the top strip, and the strip to which the remaining edges of the partition strips are sewn as the bottom strip. As the cut and marked length of fabric is advanced, the leading sewing machine of the group, the

30 needle bar of which coincides with the first indicating line, sews the continuous partition strip C (to the left) along the marked indicating line to the top strip A², the seam being just inwardly from the edge of the strip which coincides with the marked indicating line 2, as shown in Fig. 6. In the further advancement of the top strip A, the next partition strip C is sewn along the next indicating line to the top strip, and so on

35 until all of the partition strips are sewn along the indicating lines to the top strip, as shown in Fig. 5.

The top strip A with one edge of the partition strips sewn to it may then be inverted and the operation repeated to sew the opposite edges of the partition strips to the bottom strip A³, the work being done on the same group of machines or another group of sewing machines may be provided, as shown

40 in Fig. 6, arranged in like manner as previously described and located beyond the first group whereby the operation of sewing the partition strips to both top and bottom strips is continuous. When the partition

45 strips are sewn to both the top and bottom

strips, the overlapping portions of the top and bottom constituting the boxing or side walls A² are sewn together, and the covering material thus completed as shown in Fig. 7.

To complete the structure constituting the multiple collective spring enclosing compartments, the top and bottom strips, including the partition strips, are cut transversely at intervals sufficient to obtain the dimension of the cushion transversely to that obtained by the longitudinal cutting of the fabric. When this is accomplished, the multiple collective spring enclosing compartments are in the form illustrated in Figs. 1, 2 and 7, with the ends of the spring compartments open.

To close the open ends of the spring compartments separate strips may be sewn to the top and bottom pieces to form the end walls, one end of the cover being preferably closed before the springs are inserted, leaving one end of each compartment opened to admit the springs.

The springs H, are of the ordinary helical cylindric form, of substantially the height of the spring compartments of the cover. It is the practice to place the springs under initial compression before placing them into the compartments, various means being adopted for doing this. For instance, a row of springs may be placed in a jig and compressed, the jig being inserted endwise into a spring compartment, and then withdrawn, leaving the springs in place, and at the same time permitting them to expand. It is preferable, however, to separate the individual springs with fabric, in order to prevent their relative movement, as well as to deaden the scraping and creaking noises that would otherwise result in the flexing of the springs under the weight placed upon them.

To facilitate the insertion of the springs into the compartments, we have devised a method that has been found to be very satisfactory. In the first place, the same fabricated material is used which forms the cover, this material being cut transversely into narrow strips "K" of a width about one half the diameter of the springs. Each strip K, as shown in Figure 9, is therefore a short length of the cover material shown in Figure 7, and because of its formation is conveniently termed a spring retainer. These retainers would manifestly be of the same length as the spring compartments of the cushion cover to be made, and therefore different lengths of retainers would be used, depending on the width of any particularly cushion, and the number of springs in each row.

Assuming then, that the necessary spring retainers have been provided, a spring H is compressed and inserted into each cell or

compartment of the retainer and when completed, inserted endwise into each spring compartment, and anchored in place by lines of stitching *f*, passing lengthwise of the 5 spring compartments, through the top piece *A* of the cover, the ends of the springs, and the material of the spring retainers as shown in Figure 8.

This method of utilizing the same material for both covers and spring retainers makes for economy in cushion manufacture, besides providing a very satisfactory and serviceable construction.

Manifestly, certain departures may be 15 permitted in the method therein disclosed, without departing from the spirit of the invention. For instance, the covering material may be sewn in short lengths and the work done on a single machine instead of 20 the "gang" arrangement described. The continuous or gang method, however, is a matter of development toward a high state of production and efficiency, and to be attained as rapidly as conditions will permit. 25

What we claim as our invention is:

1. A method of manufacturing spring cushions consisting of sewing narrow fabric strips along their side edges to top and 30 bottom fabric pieces, along parallel spaced lines to form a cover member containing a plurality of spring compartments extending the length or width of the cushion, cutting other similarly formed fabric members 35 transversely of the narrow strips to form relatively narrow spring retaining members, inserting springs into said spring retaining members, and inserting the filled spring retaining members endwise into said compartments and closing the ends of said compartments. 40

2. A method of manufacturing spring cushions consisting of sewing narrow fabric strips along their side edges to top and bottom fabric pieces, along parallel, spaced lines to form a cover member containing a plurality of spring compartments extending the length or width of the cushion, cutting other similarly sewn together fabric 45 cover members transversely of the narrow strips to form relatively narrow spring retaining members, inserting springs into said spring retaining members, and inserting the filled spring retaining members endwise into 50 said compartments.

3. A method of manufacturing spring cushions consisting of sewing narrow fabric strips along their side edges to two lengths of fabric of a width to form the top, bottom and sides of a cushion cover 55 member, the seams being made along parallel, spaced lines, and sewing together the edges of said two pieces which are parallel with said seams, to form a cover member containing a plurality of spring compartments, cutting other similarly formed fabric members transversely of the narrow strips to form relatively narrow spring retaining members, inserting springs into said spring retaining members, inserting the filled spring retaining members endwise into the compartments of said cover member and closing the ends of said compartments. 60

4. A method of manufacturing spring cushions consisting of sewing narrow fabric strips along their side edges to two lengths of fabric of a width to form the top, bottom and sides of a cushion cover 65 member, the seams being made along parallel, spaced lines, and sewing together the edges of said two pieces which are parallel with said seams to form a cover member containing a plurality of spring compartments, cutting other cover members of similar formation, transversely of the narrow 70 strips to form relatively narrow spring retaining members, inserting springs into said spring retaining members, inserting the filled spring retaining members endwise into the compartments of said cover member and closing the ends of said compartments. 75

5. A spring cushion, comprising a fabric cover member consisting of top and bottom pieces sewn together along their edges, and a plurality of transverse partition strips 80

sewn to the top and bottom pieces along spaced lines parallel with two opposite sewn together side edges of said top and bottom pieces, said sewn together top and bottom pieces and narrow strips forming spring 85 compartments extending the length or width of the cushion, narrow spring retaining members of the same formation as the cover member and extending lengthwise in said compartments, and a row of springs contained in each spring retaining member. 90
